Attorney, Agent, or Firm—Saidman, Sterne, Kessler & Goldstein

[57] CLAIM

The ornamental design for an element of a shoe sole, as shown and described.

DESCRIPTION

FIG. 1 is a bottom plan view of an element of a shoe sole showing my new design.

FIG. 2 is a cross-section taken on line II—II of FIG. 1. The broken line showing of a shoe is environmental only and does not form part of the claimed design.

FIG. 1

FIG. 2
